UNITED STATES PATENT OFFICE

148,816

DESIGN FOR A MAGNIFIER

Henry L. Pemstein, Washington, D. C.

Application March 21, 1946, Serial No. 127,762

Term of patent 14 years

(CL. D57—1)

To all whom it may concern:

Be it known that I, Henry L. Pemstein, a citizen of the United States, residing in the District of Columbia, have invented a new, original, and ornamental Design for a Magnifier, of which the following is a specification, reference being had to the accompanying drawings, forming part thereof.

Figure 1 is a top perspective view of the magnifier shown in my new design.

Figure 2 is a side view of the magnifier.

Figure 3 is the bottom view of the magnifier.

The essential features of my design for a magnifier include the square outline with four arch shaped openings, a rounded contour above the square section, a cylindrical projection centrally mounted above this rounded part in which appears another cylindrical projection, terminating in a frusto-conical portion. The underside of the device has four arch shaped portions merging into a rounded central circular opening. The intersection of the rounded arch

shaped opening forms four diagonal lines. The opening also provides four legs of tapering section on their inner portion, terminating in legs of square cross section, upon which the magnifier rests.

I claim:

The ornamental design for a magnifier, as shown and described.

HENRY L. PEMSTEIN.
